UNITED STATES PATENT OFFICE.

FRITZ C. LUCKE D'AIX, OF NEW YORK, N. Y.

MATRIX FOR LINOTYPE OR LINE-CASTING MACHINES.

SPECIFICATION forming part of Letters Patent No. 785,478, dated March 21, 1905.

Application filed June 15, 1904. Renewed February 28, 1905. Serial No. 247,801.

To all whom it may concern:

Be it known that I, FRITZ C. LUCKE D'AIX, a citizen of the United States, and a resident of the city of New York, in the county and State of New York, have invented a new and useful Improvement in Matrices for Linotype or Line-Casting Machines, of which the following is a specification.

My invention relates to matrices employed in machines for casting lines of type, and more particularly to matrices provided each with a plurality of characters—as, for example, in Letters Patent Nos. 697,859 and 747,832; and its object is to provide matrices of this kind from which lines of characters of one and the same "body-point" or of varying body-points in any desired combination can be cast at pleasure—a result which, so far as I am informed, has not hitherto been obtained.

Body-point, as understood in the type-founders' art, refers to the style, face, height, and width of the character, and by characters of "varying body-points" I mean characters which vary between one another in style, face, height, and width.

To this end the invention consists, essentially, of a matrix provided with a series of spaces for separate characters, which spaces are of different widths, substantially as hereinafter set forth.

So far as I am aware I am the first to provide a matrix of this kind—that is to say, a matrix with a plurality of characters of different body-points, or, in other words, characters varying in style, face, height, and width.

My new matrix may be made of rectangular shape or as a straight bar, as ordinarily, or of segmental shape, as shown in my Letters Patent hereinbefore referred to.

The nature of my invention and the manner in which the same is or may be carried into effect will be readily understood by reference to the accompanying drawings, in which—

Figure 1 is a side elevation of a rectangular or straight-bar matrix embodying my invention. Fig. 2 is a front elevation of a number of such matrices assembled so as to bring into the same line characters of the same body-point. Fig. 3 is a side elevation of a seg-

mental matrix embodying my invention and of the general kind described and illustrated in my aforesaid Letters Patent. Fig. 4 is a front elevation of a number of such matrices assembled to bring into the same line characters of the same body-point. Fig. 5 is a front elevation of a set of my segmental matrices assembled in such relation as to bring into the same casting-line characters of different body-points. Fig. 6 is a side elevation of the matrices when assembled as in Fig. 5, showing also a portion of the mold 15 in which the cast line 14 is contained. Fig. 7 is a view of the line cast from the assemblage of matrices in Figs. 5 and 6. Fig. 8 is a perspective view of a matrix having a plurality of faces of three different body-points. Figs. 9 and 10 are a front and side elevation, respectively, corresponding to Figs. 5 and 6 of a modification hereinafter described.

In the matrices shown in Figs. 1 and 2 there are characters of two different body-points, 1 being a thirty-six-point-body face and 2 being an eighteen-point-body face. One of the latter is above and one is below the thirty-six-point-body face 1. That portion of the matrix-bar devoted to the thirty-six-point-character space 1 is, as seen, wider than the portions of the matrix which extend above and below it and on which are the eighteen-point-character spaces 2, there being a shoulder on each side of the matrix at the junction of the wider space with the narrower spaces. I have shown the narrower spaces 2 on but two of the matrices in Fig. 2, omitting them on the other matrices as unnecessary.

Fig. 2, represents wedge-shaped space-bands of any suitable construction.

The matrices in Fig. 2 are set up to cast the line "In the first quarter," in which the characters are all of them of one and the same body-point. The manner in which they may be transposed to cast a line in which the characters are of different body-points will be explained farther on.

In Figs. 3 and 4 the matrices are assembled to cast a line "Bold-face type," with characters all of the same body-point. 5 represents the two narrower portions for the eighteen-point-body faces, and 4 is the intermediate

95

90

95

100

wider portion for the thirty-six-point-body faces. 7 is a space-band. 6, Fig. 3, represents the cast metal line in section.

Figs. 5 and 6 illustrate how the matrices 5 may be shifted to cast a line combining the faces of different body-points. In these figures the narrower and wider character-spaces on each matrix have the same relative arrangement with respect to one another as in 10 the matrices represented in the preceding figures. They are supposed to combine two faces, a forty-eight-point-body face together with a thirty-six-point-body face of the same design of type. The forty-eight-point-body 15 face 8 is on the wider central portion of the matrix, and the two thirty-six-point-body faces 9 are on the narrower portions of the matrix-bar above and below the central space 8, respectively. In Fig. 6 the matrices 20 marked 11, 12, and 13 are side elevations of the correspondingly-marked matrices in Fig. 5, showing the relative vertical position of these matrices. The matrices in Fig. 5 are 25 assembled so as to cast the line "Rare books," combining characters of two different faces or body-points. The line cast from them is shown in Fig. 7. The manner in which they are shifted and arranged for this purpose will be readily understood by reference to the 30 figure. The first letter "R" of the line is the central forty-eight-point-body face 8 on matrix 11. The second letter "a" of the line is on the narrower portions or thirty-six-point-body faces 9 of the matrix 12, which 35 is raised until the lower character "a" on it is brought into line with the "R" on matrix 11. It will be noted that when thus placed the matrix 12 fits closely against matrix 11 throughout that portion of it which is opposite to the latter, this being due to the 40 "stepped" formation of the sides of the matrices. The third character "r" of thirty-six-point-body face is obtained by depressing the third matrix 13 until its upper narrow portion 45 9 is brought into line. The next matrix, with similar point character "e," is raised until its lower narrower space 9 is brought into the line, and so on. In short, on each matrix the character-space of the greatest 50 width occupies the longitudinal center of the matrix and the character-spaces of less width are duplicated, there being one space for each character of less width both above and below the single central character-space of greatest 55 width, and as the character-spaces progressively decrease in width, each character-space of less width is further removed from the center space. This is indicated clearly in Fig. 8, where the matrix—a straight-bar matrix—carries the character "R" in three different point-body faces. The stepped formation of the matrix on each side is plainly illustrated in this figure.

The duplication of the smaller or narrower 60 spaces and locating the two spaces of each

pair one above and one below the central widest space is because, considering the widest character-space as the median line, it is necessary in setting up successive characters of less space width to lift and lower the successive matrices alternatively, so as to bring into line the lower character-space on the one matrix and the upper corresponding character-space on the next succeeding matrix; otherwise the stepped matrices would not fit together, as they are shown to do in Fig. 5, so as to form a solid casting-line.

In Fig. 5 the parts marked 10 are space-bands. In Fig. 6 the part marked 15 is a portion of the mold. The cast line is shown in 80 elevation at 14.

I provide the matrices, as shown in Figs. 1, 3, 5, and 8, with a plurality of notches 16 on their rear edges corresponding in number and location to the characters on the front 85 edge of the matrix. These notches are designed to engage a suitable device which when the selected character-space on the front edge of the matrix has been brought into line will engage the notch 16 on the rear edge of 90 the matrix appropriate to that space, and thus firmly hold the matrix in its adjusted position. I have not deemed it necessary to illustrate any such device, inasmuch as mechanism for this general purpose is old in linotype-machines and besides forms no part of my present invention.

From the foregoing it will be seen that the characteristic of the invention is that the matrix has a plurality of character-spaces of 100 varying widths to receive characters (whether in intaglio or in relief) representing the same letter or sign. The character-spaces of decreasing width may be arranged either above or below, or both above and below, the character-space of greatest width, or, in other words, the matrices may be stepped both above and below the center character-space or space of greatest width, (which is the arrangement illustrated in the drawings,) or it 105 may be stepped either above or below that space. This last-mentioned modification is illustrated in Figs. 9 and 10, where the matrices are each of them stepped either above or below the character-space of greatest width. 110 They are shown assembled in Fig. 9 so as to cast the line "Rare books," combining character-spaces of two different widths or body-points. Fig. 10 is a side elevation of the matrices when assembled as in Fig. 9, showing 115 also a portion of the mold. These figures, *mutatis mutandis*, correspond, respectively, to Figs. 5 and 6, and will be understood without further description, the only difference between them being that in Figs. 9, 10 there is 120 but one step to the matrix, the narrower portion 9 being either above or below the wider portion 8, while in Figs. 5 and 6 the narrower portions are duplicated, as hereinbefore described. Other variations also can be made 125 130

in the matrices without departure from my invention. I therefore do not limit myself to the structural details hereinbefore set forth in illustration of my invention, but

5 What I claim, and desire to secure by Letters Patent, is as follows:

1. A matrix for line-casting machines provided with a plurality of character-spaces of various widths, the widest character-space at 10 the center and the narrower spaces in pairs for each character, one above and one below the center space, each pair of spaces being narrower than the next adjoining pair which intervenes between it and the central charac-

ter-space, substantially as and for the purposes 15 hereinbefore set forth.

2. A single-character matrix for line-casting machines provided with a plurality of character-spaces of different widths bearing letters or signs which are the same in all the 20 character-spaces but differ between themselves in style, face, height and width.

In testimony whereof I affix my signature in presence of two witnesses.

FRITZ C. LUCKE D'AIX.
